UNITED STATES PATENT OFFICE.

GEORGE K. DAVOL, OF SAN FRANCISCO, CALIFORNIA.

FUEL-VALVE FOR INTERNAL-COMBUSTION ENGINES.

1,225,703.

Specification of Letters Patent.

Patented May 8, 1917.

Application filed November 12, 1912. Serial No. 730,881.

To all whom it may concern:

Be it known that I, GEORGE K. DAVOL, a citizen of the United States, residing in the city and county of San Francisco, in the State of California, have invented a new and useful Form of Fuel-Valve for Internal-Combustion Engines, of which the following is a specification.

My invention relates to a form of valve, or fuel injector, through which fuel is introduced, or intermittently sprayed, into the cylinder, or combustion chamber, of an internal combustion engine.

This form of valve which embodies my invention, is primarily designed to operate with a liquid fuel, but a mixed liquid and gaseous fuel—, such as a partially vaporized oil, or a mixture of oil and air, may be used with this valve, as may also a semi-liquid fuel carrying solid matter.

In most internal combustion engines operating on oil-fuel and employing high compression of the air in the cylinder, the oil fuel is injected or driven into the cylinder and atomized at the same time by means of air compressed to a very high pressure, or a pressure several hundred pounds in excess of that to which the main body of air in the cylinder is compressed by the working piston. The necessary means for providing this highly compressed injection air in such engines, comprising a multi-stage compressor with intercooler, forms a complicated and troublesome feature of such engines, and it is highly desirable, if possible to do so, to eliminate the necessity of employing this injection air for spraying the fuel into the cylinders.

My invention, while not necessarily limited to operation on liquid fuel alone, is intended primarily to afford a means of properly introducing liquid fuel into the cylinder of an internal combustion engine in a finely divided and diffused state without resorting to the use of atomizing or injecting air.

The effect of this is to render such engines much simpler and also to do away with the objectionable cooling effect of the atomizing air which is often experienced when such engines are running on light loads.

Many devices for accomplishing this end have been proposed, and it is possible by forcing the oil fuel through a contracted and properly formed orifice under extremely high pressure to atomize the oil very effectively without resorting to the use of any

atomizing air. It has been found, however, that if such orifices are made of such form as to properly divide or diffuse the oil, there is much difficulty experienced from the oil fuel clogging the orifice, largely through the effect of the heat of combustion, and the intermittent action of the sprayer; causing deposits of residue or carbon to form in the orifice, or on the edges of the orifice.

My invention is, therefore, largely concerned in providing an orifice of form such as will most effectively break up and spray the oil fuel and diffuse it properly throughout the combustion space, and which at the same time is kept clear of all deposits of residue or carbon or of foreign matter carried by the oil.

The spraying or injecting orifice I employ is preferably formed by a conical or approximately conical valve resting on a correspondingly formed seat and preferably opening inwardly into the cylinders.

This valve I keep clear of clogging accumulations by providing means, whereby it is turned or oscillated axially while bearing on its seat. This twisting or oscillation of the valve against its seat, which occurs between or during each injection of fuel, clears or grinds away any deposit or matter tending to clog the orifice.

In the accompanying drawings.—

Figure 1 is a section taken longitudinally through the center along the axis of the valve.

Fig. 2 is a section at right angles to the axis and on the line $x-x$ of Fig. 1.

Fig. 3 is a similar cross-section taken on line $y-y$ in Fig. 1.

Fig. 4 is a similar cross-section taken on line $w-w$ in Fig. 1.

Fig. 5 shows a modified form of my invention and is a longitudinal central section taken along the axis of the valve.

Similar parts shown in the various views are designated by the same reference numbers in all the views.

Referring to Fig. 1—A portion of the cylinder head 1 of an internal combustion engine is shown, the interior of the cylinder or the combustion space being shown at 2. The valve body 3 is secured to this cylinder head 1 by two studs 4 which are shown in plan in Fig. 3. Into the valve body 3 is screwed the valve seat 5 forming a tight joint with the valve body.

The valve proper 6 when fuel is not being

injected rests on the seat 5 and is held in place by the helical spring 7 which acts against the end piece 8 which is pinned to the inner end of the stem of the valve 6 by the pin 9. The other end of the spring bears on the valve seat 5.

This arrangement holds the valve 6 against its seat 5 by the force of the spring 7 unless forced off its seat by pressure of the 16 fluid fuel or by some mechanical means.

The upper end of the part 8 is formed with a flat central projection which engages loosely with a jaw formed in the lower end of the spindle or valve 10 so that while 15 free to move axially independently of the part 10, it can be turned or twisted on its seat by any turning movement of the part 10.

The preferred form of my device is shown in Fig. 1 and comprises a plunger 11 and 20 suction valve 10. The plunger 11 is reciprocated by any suitable connection to the moving parts of the engine and is a close fit in the hole bored in the valve body 3 and is provided with the gland 12 and stuffing box 13 25 making it tight against leakage.

The suction valve seat 14 is secured at the upper end in the valve body 3 tightly against leakage of oil by the clamping nut 15 and forms at its upper end the stuffing box 16 30 through which the stem of the suction valve 10 passes.

The suction valve 10 is given both an axial and an oscillating or turning movement by means which I shall now describe.

[35] On the upper end of the valve body 3 is formed a helical thread or threads 34 of steep pitch, and fitting on this threaded portion is the nut 17. This nut 17 has an arm 18 by means of which it is oscillated through 40 any suitable connection with the moving parts of the engine. Into the top of the nut 17 is screwed the adjusting screw 19 which is bored centrally and in this central bore slides freely the thimble 20, which is pinned 45 fast to the suction valve stem by the pin 21. This pin 21 extends on each side through slots formed in the adjusting screw 19 so that while the thimble 20 and valve stem 10 are 50 free to move axially with reference to the adjusting screw 19 they must turn or oscillate with it. Against the lower end of the thimble 20 bears the helical spring 22, which has bearing at its lower end on the reentrant portion of the nut 17.

55 The adjusting screw after being properly adjusted is held from turning in the nut 17 by the screw 23.

In the position of the parts shown in Fig. 1, the suction valve 10 bears against its seat 14, the spring 22 tending to keep it in this position. If the nut 17 be turned so that it moves down on the threaded portion of the body 3, the end of the suction valve stem 10 will come in contact with the top portion of 65 the adjusting screw 19 and further move-

ment of the nut will cause the valve 10 to be forced off its seat; it being at the same time turned on its axis, following such movement of the nut 17 and imparting such turning movement to the valve 6. Any upward movement of the nut 17 from the position shown in Fig. 1 while causing the suction valve 10 and valve 6 to turn on their axes, would not cause the suction valve to move in an axial direction, as it already bears against its seat, but would result in a compression of the spring 22.

70 The action of the apparatus will now be explained.

The spraying valve 6 is held tightly on its seat both by the action of the spring 7 and by the pressure of the working gases within the cylinder of the engine, except when fuel is being injected, when it is forced off its seat by the pressure of the fuel, which thus opens 85 an orifice for itself through which it is projected with high velocity in a conical shaped film or spray into the cylinder.

The suction valve 10 is held off its seat by the nut 17 except during the period of fuel 90 injection.

The plunger 11 is so reciprocated by suitable connection to the moving parts of the engine that the period of injection of fuel will occur during its inward stroke or movement toward the axis of the valve. The suction valve 10 being held off its seat during the outward stroke of the plunger, it will be understood that the outward stroke of the plunger 11 will cause the liquid fuel 95 to be drawn from a source of supply through the pipe 24, annular passage 25 and between the valve 10 and its seat 14 into the chamber 26. On the reverse or inward stroke of the plunger, this current or liquid fuel 105 will be, of course, reversed, and the oil would be forced back again to the source of its supply if the suction valve 10 was held continuously off its seat.

During this return or inward stroke of the plunger 11, however, the period of fuel 110 injection occurs, and the oscillating movement of the nut 17 by suitable connection with the moving parts of the engine, is so timed that it then reaches the highest point 115 of its upward travel and during a certain determined period of the highest portion of its travel it allows the valve 10 to contact with its seat; as shown in Fig. 1. At this period, the plunger is moving on its inward 120 stroke and liquid fuel being cut off by the closing of the suction valve 10 from returning through it, is forced through the only other avenue of escape, or through the valve 6, which it lifts off its seat and so escapes 125 into the cylinder of the engine.

Preferably before the plunger 11 has completed its inward stroke, the oscillating movement of the nut 17 has caused it to descend sufficiently to lift the suction valve 130

off its seat again and so allows the oil under pressure of the plunger 11 to escape or pass back to the source of supply. Immediately the suction valve lifts, relieving the pressure, the spraying valve 6 seats itself and the injection of oil into the cylinder ceases.

It will be seen by this arrangement that the high pressure necessary to properly spray the oil into the cylinder exists only during the period of injection and that this high pressure is cut off by the suction valve from the stuffing box 16 which is not, therefore, called upon to resist a high pressure. It is also to be noted that the differential or excess pressure of injection under which the fuel is forced into the cylinder is regulated by the pressure of compression of the spring 7 and is independent of the speed of the engine; also that the rate at which the oil is injected into the cylinder is always proportioned to the speed of movement of the plunger 11 and therefore the fuel can be evenly fed or injected at an approximately uniform rate throughout any desired period.

From the foregoing, it is understood that the spraying valve 6, together with the suction valve 10 and nut 17 are all oscillated through a certain angle about their axes and back again, during each cycle of the engine. The valve 6 resting on its seat most of this time grinds its seat free of obstructions or deposits and by its movement prevents any serious formation of deposits on the edges of the orifice opening into the cylinder of the engine. The suction valve 10 is only seated for a comparatively brief period or during the period of injection, and as the reversal of movement of the oscillating parts occurs during this period, the valve 10 is moved but very slightly upon its seat.

In the drawings and the foregoing description, I have shown and described the plunger 11 as working in a cylinder formed in the valve body 3 which arrangement I have adopted for simplicity of description. This exact arrangement of the plunger is not necessary nor in my opinion to be preferred. The plunger can operate in a cylinder placed at any convenient point for connection to the moving parts of the engine and connected with the chamber 26 in the valve body by means of a pipe, through which the oil or fuel will pass back and forth with the movement of the plunger.

In Fig. 5, I show a modified form of valve in which the spraying valve opens outwardly away from the cylinder. In this form the oil fuel is supplied through the pipe 27 from any suitable source, under either constant pressure or intermittently varying pressure. As the spraying valve 6^a here opens outwardly, the pressure of the fuel cannot open it but tends to keep the

valve on its seat. In this form the spraying valve 6^a is therefore lifted off its seat mechanically.

Referring to Fig. 5, the adjusting screw 19^a carried by the oscillating nut 17^a is pinned fast by the pin 28 to the spindle 29. This spindle 29 passes through the stuffing box 16^a into the space 26^a which is connected to the source of supply of fuel.

The spindle 29 has an enlarged lower end, 75 which is bored axially to receive the upper end of the spraying valve 6^a which slides loosely within the said hole. There are two slots 30 on opposite sides of the said hole and through these slots and through a hole in 80 the upper end of the stem of the valve 6^a is passed the pin 31. It can be seen that any twisting or oscillating movement of the spindle 29 will be transmitted to the valve 6^a by means of the pin 31 which fits loosely 85 in the slots 30. Also it can be seen that a certain movement in an axial direction is allowed the spindle 29 without affecting the valve 6^a, but if the spindle be raised far enough the pin 31 will contact with the bottom 90 of the slots 30 and any further movement of the spindle in the same direction will cause the valve 6^a to be lifted off its seat. The spring 33 together with the pressure of the fuel acts to keep the valve 6^a normally on its seat. The valve 6^a is guided at 95 its lower end by the guide vanes 32.

The action of this form of valve can now be readily understood.

The arm 18^a of the nut 17^a is connected by 100 suitable means with the moving parts of the engine, so that at the desired time of fuel admission, the nut 17^a is at the highest point of its travel. The parts are so adjusted that during a certain determined period embracing the period at which the nut 17^a reaches its highest point of travel, the pin 31 is in contact with the bottom of the slots 30 and the valve 6^a is lifted off its seat, and fuel under the pressure of the source of supply is 110 forced into the engine cylinder. On the downward movement of the nut the valve 6^a is dropped on its seat again and the fuel is cut off.

The oscillating movement of the nut on 115 its axis is transmitted to the valve 6^a by the means described and the valve, forced against its seat by the pressure of the fuel, and by the spring 33, turns through a certain angle back and forth on its seat, breaking down and grinding away any obstructions or deposits and keeping the seat clear.

The valve may be placed either vertically as herein described, or horizontally and many arrangements of parts other than 125 those described may be used without departing from my invention.

It must be understood that although I prefer a reciprocating plunger, acting to draw the fuel back and forth through the 130

suction valve 10, as indicated in Fig. 1, a continuous forced supply of fuel may be employed, supplied to the chamber 26, Fig. 1, from any suitable source, at any desired 5 and determined rate, and allowed to pass on and escape through the valve 10 when the valve 10 is open, but which when the valve 10 is on its seat must escape or vent itself by lifting the valve 6 off its seat and so injecting itself into the cylinder of the engine. 10

In other words, it is not necessary that the fuel be drawn through the valve 10 into the chamber 26 or that the valve 10 act as a suction valve, as the same end may be accomplished by supplying fuel to the chamber 25 by other means and allowing the valve 10 to afford escape of the fuel except when it is closed during the fuel injection periods. I have, therefore, in the accompanying claims 15 referred to the valve 10 as an escape valve as well as a suction valve. 20

I wish to point out that the movement which I prefer to give to the spraying valve on its seat is a reversed oscillation, that is, 25 the valve is moved on its seat angularly in opposite directions, being first twisted or turned in one direction and then in the other, returning at the end of such double oscillation (which is carried out completely 30 during each engine cycle) to its original position.

This reversed oscillating movement in the grinding of valves on their seats is much more effective movement than a simple intermittent or continuous rotating movement 35 in one direction; which rotating movement or movements in one direction have a tendency to cut circular grooves on the surfaces of the valve and seat, and do not as effectively yield the smooth and good results 40 that the reversed oscillating movement does.

It is also to be noted that the most advantageous period in which to move the valve on its seat to effect a grinding away of 45 deposits, is just as the valve is coming back on its seat after the period of opening, and during the first instant of its being in contact with its seat, and this action it is to be noted I have carefully provided for.

50 5. What I claim is:

1. In a fuel injecting apparatus for internal combustion engines, the combination of a spraying valve, a spring or other yielding means for holding said valve against its 55 seat, means for imparting angular movement to said valve immediately upon closing and while so held against its seat, and means for forcing liquid fuel between said valve and its seat against the action of said spring or other yielding means.

60 2. In a fuel injecting apparatus for internal combustion engines, the combination of a spraying valve opening inwardly into the cylinder of the engine and held on its seat 65 by a spring or other yielding means, means

for intermittently forcing liquid fuel between said valve and its seat, and means for turning or oscillating said valve on its seat in opposite directions.

3. In combination, an annular valve seat, 70 a valve for said seat, yielding means for holding said valve upon its seat, means for periodically forcing liquid fuel between the valve and the seat against the action of said yielding means, and means for oscillating said valve upon its seat in opposite directions between successive periods of fuel injection. 75

4. In a fuel injecting apparatus for internal combustion engines, the combination of a chamber, means of supplying fuel to said chamber, a spraying valve placed between said chamber and the engine cylinder, means for periodically twisting or oscillating said spraying valve on its seat, an escape valve when open permitting the fuel to escape from said chamber, and means for opening and closing said escape valve. 80

5. In a fuel injecting apparatus for internal combustion engines, the combination of a chamber, a passage or port connecting said chamber with the engine cylinder, a spraying valve closing said passage or port except during the periods of fuel injection, a spring or other yielding means forcing said 95 spraying valve on its seat, means for periodically imparting angular movement to said spraying valve immediately upon closing and while held against its seat by the said spring or other yielding means, and 100 means for periodically establishing a fluid pressure of liquid fuel within the said chamber, the said pressure being sufficient to force the said spraying valve off its seat against the action of the said spring or other 105 yielding means.

6. In a fuel injecting apparatus for internal combustion engines, the combination of a chamber to which fuel is supplied, a spraying valve between said chamber and the engine cylinder, an escape valve when open 110 allowing fuel to pass from said chamber, connection between the two said valves whereby angular movement of said escape valve on its axis is transmitted to said 115 spraying valve said two valves being independently capable of reciprocation.

7. In a fuel injecting apparatus for internal combustion engines, the combination of a chamber to which fuel is supplied, a spraying valve between said chamber and the engine cylinder, an escape valve when open 120 allowing fuel to pass from said chamber, the said two valves being in axial line, means for twisting or oscillating said escape 125 valve on its axis, and means for transmitting oscillating or twisting movement from said escape valve to said spraying valve said two valves being independently capable of reciprocation.

8. In a fuel injecting apparatus for internal combustion engines, the combination of a reciprocating plunger, a chamber into which fuel is drawn by said plunger, a suction valve through which fuel passes into said chamber, a spraying valve placed between said chamber and the engine cylinder, means for imparting to said suction valve oscillating or twisting movements on its axis, and means for transmitting such oscillating or twisting movements from said suction valve to said spraying valve.
9. In a fuel injecting apparatus for internal combustion engines, the combination of a reciprocating plunger, a chamber into which fuel is drawn by said plunger, a suction valve placed between said chamber and a source of supply of fuel, a spraying valve placed between said chamber and the engine cylinder, the two said valves being in axial line, means for imparting oscillating or twisting movements to said suction valve, and means whereby oscillating or twisting movement is transmitted from said suction valve to said spraying valve.
10. In a fuel injecting apparatus for internal combustion engines, the combination of a chamber to which fuel is supplied, an escape or suction valve placed between said chamber and source of supply of fuel, a spraying valve placed between said chamber and the engine cylinder, mechanical means for imparting opening and closing movements to said escape or suction valve, means for twisting or turning said escape valve on its axis, and connecting means between said escape valve and said spraying valve whereby twisting or turning movements are transmitted to said spraying valve.
11. In a fuel injecting apparatus for internal combustion engines, the combination of an engine cylinder, a spraying valve opening inwardly into said cylinder, a mechanically controlled suction valve, means for twisting or turning said suction valve on its axis, and means for transmitting such twisting or turning movements to said spraying valve and means for independently operating said valves.
12. In combination, an annular valve seat, a valve therefor, spring means for holding said valve upon its seat, means for imparting an axial movement to said valve against said spring means sufficient to force said valve from said seat, said means comprising a fluid pump, and means independent of said lifting means to impart an angular motion to said valve while it is pressed against its seat by the said spring.
13. In combination, an annular valve seat, a valve, a spring for holding the said valve against the seat, means for periodically injecting liquid fuel between the valve and the seat against the action of the spring, and means for periodically imparting angular motion to the valve upon the seat immediately upon closing of the valve and while it is pressed against the seat by the said spring.
14. In combination, an annular valve seat, a valve, a spring for holding the valve against the seat, means for periodically injecting liquid fuel between the valve and the seat against the action of the spring, and means for periodically imparting angular motion to the valve as it approaches its seat during the closing movement of the valve and immediately upon closing while it is in contact with its seat.

In witness whereof, I hereunto subscribe my name this 2nd day of November, A. D. 1912.

GEORGE K. DAVOL.
